UNITED STATES PATENT OFFICE.

FRANK CARTWRIGHT, OF TRENTON, NEW JERSEY, ASSIGNOR TO THE GEO. W. BLABON CO., OF PHILADELPHIA, PENNSYLVANIA, A CORPORATION OF PENNSYLVANIA.

DESIGN FOR LINOLEUM OR SIMILAR HARD-SURFACED COVERING.

Application filed August 29, 1925. Serial No. 14,657. Term of patent 3½ years.

To all whom it may concern:

Be it known that I, FRANK CARTWRIGHT, a citizen of the United States, residing in the city of Trenton, in the county of Mercer and State of New Jersey, have invented a new, original, and ornamental Design for Linoleum or Similar Hard-Surfaced Covering, of which the following is a specification, reference being had to the accompanying drawing, forming a part thereof.

The figure is a plan view of a section of linoleum or similar hard surfaced covering showing my new design.

I claim:

The ornamental design for linoleum or similar hard surfaced covering as shown.

In testimony whereof I have hereunto set my hand this 25th day of August, 1925.

FRANK CARTWRIGHT.
